STRINGED MUSICAL INSTRUMENT

Walter J. Pelensky, 19C Manheim Gardens,
Philadelphia, Pa. 19144

Filed Mar. 28, 1968, Ser. No. 11,178

Term of patent 14 years

Int. Cl. D17—03

U.S. Cl. D56—1

Fig. 1

Fig. 3

Fig. 2

Fig. 4

FIG. 1 is a perspective view of a stringed musical instrument, specifically, a Ukrainian torban (Ukrainian styles of Theorbo), showing my new design;

FIG. 2 is a face view;

FIG. 3 is a side elevational view; and

FIG. 4 is an opposite side elevational view thereof.

Portions of the drawings are shaded to indicate contrast.

I claim:

The ornamental design for a stringed musical instrument, as shown and described.
